PERCUSSION DRILL

Colson J. Endsley, Los Angeles, Calif.

Application March 5, 1937, Serial No. 129,225

7 Claims. (Cl. 255—41)

The present invention relates to improvements in percussion drills and refers particularly to a rotary device for operating such drills.

The device to which the present improvements pertain is fully described in Patent No. 1,995,504 issued to me on March 26, 1935. This patent covers a rotary device provided with a series of balanced hammers, and the improvements herein described are directed to means for making the 10 operation of such device more convenient and effective.

To this end, it is an object of the invention to provide a more positive means for stopping the hammers which have been set in motion upon 15 striking the drill. A further object is the provision of means for adjusting the device to various angles of inclination. Another object is to provide means for advancing the hammers relative to the advancement of the drill. A further 20 object is to provide means for rotating the drill axially while the hammers are in operation. The further objects and important features of the invention are hereinafter fully described and illustrated in the appended drawings, of which:

25 Fig. 1 is a side elevation of a structure embodying the invention. Fig. 2 is a fragmentary view illustrating on a larger scale some of the more important parts of the invention, Fig. 1. Fig. 3 is an end elevation, parts of Fig. 1, substantially in agreement therewith, and Fig. 4 is a side elevation of portions of the device, illustrating parts which could not conveniently be shown in Fig. 1 without obscuring other important features of the invention.

30 The structure of the invention in the preferred form shown in the drawings comprises a post 1, which for convenience is shown set on a base 2. A bracket 3 is mounted to slide axially on the post, and it is held in adjusted position by means 35 of a set screw 4. A rail 5 is pivotally secured to this bracket, at 6, and it is shaped to support a 40 slideable member 7, provided with a boss 8, which forms a bearing for a drive shaft 9, which in turn is adapted to support the main rotating frame 10 of the invention. This frame is star-shaped and is fitted at the points pivotally to support pairs of 45 balanced hammers 11. From this, it is seen that the frame 10 is mounted to rotate on the shaft 9 of the slideable member 7 and that it is adjustable 50 with this member along the rail 5. From the slide 7 rises a bracket 12, terminating at the top in a sleeve 13, within which the drill 14 is fitted to slide longitudinally. A sprocket 15 is fastened to the drive shaft 9 and a chain 16 connects this 55 sprocket with the second sprocket 17 of a spindle

18, which is mounted to rotate on the sleeve 13. A worm 19 is secured to this spindle and positioned to rotate a wheel 20, which in turn is perforated to ride on a squared portion of the drill 14. From this it is seen that rotation of the 5 drive shaft 9 communicates rotation to the drill.

A second bracket 21 is adjustably mounted on the post 1 and held in position by means of a set screw 26. The upper end of this bracket is perforated to receive a pin 22 which rides in a 10 slot 23 of the rail. This combination makes it possible to adjust the bracket 3 on the post relative to the bracket 21 in order to change the angular relation of the rail to the post and thereby to permit the operator to adjust the drill to various 15 angles of inclination.

It is often desirable to mount a drill vertically and it is convenient for this purpose to provide a sleeve, similar to the sleeve 13, for guiding the drill in this position or, if preferred, it is possible 20 to make the sleeve 13 detachable from the bracket 12, as indicated by means of the clamping bolt 25. The sleeve may then be detached and mounted on the bracket 21, in the position indicated in dotted outline in Fig. 1, whereupon the 25 chain 16, which preferably has been detached during this operation, may again be mounted on the wheel 17.

In the manner substantially as above described, it is possible to direct a drill to suit operating 30 conditions.

In the patent above referred to, resilient means were provided for stopping the rotation of the hammers, caused by impact against the drill, and while such means appeared quite satisfactory, experience has taught me that positive devices for stopping the hammer rotations are much to be preferred. Such means is, in Fig. 2, shown to comprise an annular member 40 secured to the hub 11^a or handles 11^b of the hammers 11 in any suitable manner, as by welding the members to the hammer handles. Diametrically opposed stops 42 and 43 are mounted within this member and these stops normally take a position perpendicular to the radial center line of the frame arm 41. A yoke shaped member 44 is mounted to straddle the end of each arm 41 and this member is fitted pivotally to support pawls 45 and 46 which, by means of suitable springs 47 and 48, are normally held engaging the stops 42 and 43. To 50 this end it is, of course, necessary to shape the stops to project sidewise sufficiently to engage the ends of the pawls. On the slide 7 is mounted a projection 56, positioned in the path of travel of a bell crank 49, which in turn is pivotally se- 55

cured to the arm 41, there being one bell crank on each arm. Sliding bars 50 and 51 are pivotally secured to the outer extremities of this bell crank, and they normally extend to a point 5 near the inner end of the pawls 45 and 46. This position is indicated on the arm at the left side of Fig. 2. As the frame 10 commences to rotate, it is seen that the bell crank 49 of this arm strikes the projection 56, causing the bell crank to tilt 10 and to push the sliding bar 50 forward, thereby to withdraw the pawl 45 from the stop 43. This position is indicated at the top of Fig. 2, but it is important to remember that this position is attained while the arm is in its lowermost position. 15 The perforations 50^a, 51^a, at the inner end of the bars 50, 51 are, in Fig. 2, shown transversely elongated in order to afford the studs 49^a of the bell cranks 49, freedom to swing from normal into tilted position.

20 Continued rotation of the frame causes the hammer 11 to strike the drill 14 and, as the pawl 45 has been withdrawn from the stop 43, it is seen that the hammer is free to yield, causing the sidewise projection of the stop 43 to strike the 25 upper end of the sliding bar 50 and to force this down into its original position. Release of the pawl 45 is thereby effected and its spring 47 is permitted to push the pawl back into the path of the stop 43. From this, it is seen, that nearly 30 one-half of a revolution is allowed in which to reset the pawl 45. If the projection 56 were placed at the top instead of at the bottom the pawl would have to act so quickly that it might not return in time to catch the stop.

35 While, in the patent above referred to, the revolving frame was operated by a hand crank, I prefer in this case to perform the operation by means of a wheel 60, as indicated in Figs. 3 and 4. One reason for this is that a hand wheel may be found more convenient to operate, but 40 the employment of such operating wheel has another advantage, which now will be described. In Fig. 3, I have shown an annular member, or tire 61, of the same diameter as the wheel 60 and fitted with an extension 62, which is shaped 45 to engage periphery of the annular members 40. In order to mount this tire, it is required to move the hammers into the position shown in Fig. 4 and to unscrew the nuts 63. The projection, 62, of the tire, is bifurcated to straddle the bolt of 50 this nut, which latter thereupon is remounted to lock the tire in position. When this tire is mounted on the revolving frame, it is seen that two wheels are provided, on which the device of 55 the invention may be perambulated upon lifting the lower end of the post off the ground and using it as a tongue by means of which to propel and steer the vehicle in this manner provided, substantially as indicated in Fig. 3.

60 When the hammers rebound, they develop considerable speed, causing the stops within the annular members 40 to strike the stop pawls with so much force that the repeated hammering may damage the parts. In order to cushion these 65 blows, I have made the yoke members 44 slidably on the ends of the frame arms. A spring 65 maintains each member advanced against stops 66. As the pawls 45, 46 are mounted on this yoke member, it is seen that the latter is able to yield 70 against the tension of the spring and thereby to absorb the shock of the hammer impact.

As stated, means is provided for advancing the hammer frame relative to the advance movement of the drill. The mechanism illustrated for this 75 purpose is, for the sake of simplicity, shown to

comprise a hand lever 70, fitted with a pawl 71, riding in teeth 72 of the slide 7. As the hand lever is pivotally fixed on the rail 5, it is seen that a slight elevation of this lever suffices to advance the slide. A stop 73 may be provided, against 5 which the lever, dropping by gravity, may be arrested.

As shown in the drawings, the device is set to drill left-handed, the operating wheel being on the right side of the post. It may, however, frequently be required to drill right-handed, and this may readily be prepared for in the following manner. The slide 7 is first pushed forward, past the pivotal point 22, whereupon the bolt at 6 is removed. It is now noticed that the bracket 15 21 is divided at the top to provide a vertical pivot 27, on which the rail 5 can be given a one-half turn, whereupon it again is clamped in position. It is then only required to swing the bracket 12 in the opposite direction and to readjust the 20 sleeve 13, and the device is ready for right-hand operation.

The structure herein described is merely illustrative of my invention and may be modified to the extent covered by the appended claims. 25

I claim:

1. In a percussion drill, a post, a star-shaped frame mounted for rotation on said post, balanced pairs of hammers mounted for rotation on the points of said frame, a drill supported by said post in the path of travel of said hammers, stops mounted to rotate with the hammers, means on said frame normally engaging said stops to maintain the hammers non-rotatable in a predetermined fixed position, and means on said post positioned to actuate said stop engaging means successively to release said hammers before reaching said drill, the rebound of the hammers upon striking the drill resetting said stop engaging means. 35

2. In a percussion drill, a support, a member pivotally mounted on one side of said support, a series of balanced pairs of hammers pivotally mounted on said member, a drill longitudinally slidable on said support in the path of travel of said hammers, means for rotating said member to cause the hammers to strike said drill, and means for shifting the member to the opposite side of said support. 40

3. In a percussion drill, a post, a bracket pivotally mounted on said post, a star-shaped member pivotally mounted on said bracket, a plurality of balanced hammers mounted to rotate at the points of said member, a hand wheel on the pivot of the member for rotating said member, the diameter of said wheel being greater than the outside diameter of said member, and an annular member of the same diameter as the said wheel attachable to said member, the wheel and the said annular member combining to form two wheels upon which to roll the device along the ground. 50

4. In a percussion drill, a post, a rail on said post and inclinable relative to the post, a member longitudinally slidable on said rail, a drill 65 slidable in said member, a star-shaped frame mounted to rotate on said member, balanced hammers pivotally mounted at the points of said frame for striking said drill, said hammers being free to rebound upon striking the drill thereby 70 to rotate said hammers, and means for positively arresting the hammers in striking position.

5. In a percussion drill, a rotatable frame, a series of striking devices mounted on said frame in normal balance, each device comprising a pair 75

- of hammers on the ends of a common handle pivotally mounted on the frame midway between the hammers, a pair of diametrically opposite stops mounted on the hammers to rotate with the hammers of each pair, a pair of pawls on the frame normally engaging said stops to maintain the hammers non-rotatable in striking position, and pawl withdrawing means for actuating said pawls for releasing each pair of hammers for recoil rotation before one of the hammers strikes, said means actuated by the hammers upon recoil rotation thereof to actuate the pawl withdrawal means to release the pawls to again lock the hammers in striking position.
6. In a percussion drill, a post, a support vertically adjustable on said post, a member slideable on said support, a drill support on said member, a frame mounted for rotation on said member, a series of pairs of balanced hammers pivotally mounted on said frame to strike a drill in said drill support when the frame is rotated, means normally maintaining said hammers non-rotat-

able in striking position, and means actuating said hammer maintaining means for releasing the hammers for rotating before reaching striking position, said releasing means being reset upon rotation of the hammers again positively to lock the hammers in striking position. 5

7. In a percussion drill, a support adjustable to various angles of inclination, a slide on said support, a drill holder mounted on said slide, a frame rotatably fixed on the slide, hammers pivotally mounted on said frame in balanced pairs, means normally locking each pair of hammers in position for one hammer to strike a drill in said holder when the frame is rotated, means for releasing each pair for recoil rotation before striking, means actuated by frame rotations gradually to advance the drill in the holder, and manual means for advancing said slide to readjust the position of the advanced drill relative to the hammers. 10 15 20

COLSON J. ENDSLEY.
